Application January 14, 1953, Serial No. 331,272

9 Claims. (Cl. 154—41)

The present invention relates to a method and apparatus for applying pressure-sensitive tape to cylindrical or other objects. The method and apparatus in accordance with the invention are particularly suitable and useful for applying tape to pipe. In order to simplify the following description and claims, reference is made to wrapping pipe with pressure-sensitive tape but it will be understood that the invention is not limited to the wrapping of pipe and that the term "pipe" is herein used in an illustrative rather than a restrictive sense.

It has been found advantageous to wrap pipe with pressure-sensitive tape, for example to protect the pipe against corrosion. Tape suitable for such use comprises a strip, band or ribbon of flexible material, for example fabric, plastic or paper coated on one side with a tacky adhesive having the characteristic of adhering to a dry surface when pressed against it without the need of applying any wetting agent or solvent to the tape. Such tape is available on the market under the trade name "Dressertape." The tape is customarily supplied in a roll wound on a core having an axial bore or hole and may be of various sizes. For example, tape suitable for wrapping pipe may be purchased in a roll about four inches long (this being the width of the tape), and about six and one-half inches outside diameter, with an axial hole about one and one-quarter inches in diameter.

In wrapping pipe by hand with pressure-sensitive tape, difficulty is experienced in applying the tape to the pipe smoothly and uniformly with predetermined overlap of successive convolutions of the tape. If the tape wrinkles when being wrapped on the pipe, the wrinkles may provide minute channels or passageways through which moisture can reach the pipe to cause corrosion. The maintenance of uniform overlap is also highly important. If the overlap is insufficient, the pipe is not properly protected. If the overlap is excessive, it results in a waste of the tape which is relatively expensive.

Difficulty is also experienced in wrapping pipe outdoors in cold weather. When the temperature is low, the tape will not adhere properly to the cold pipe. While adhesion can, in some instances, be improved by preheating the pipe, this is not ordinarily practicable, particularly if the pipe is already in service.

It is an object of the present invention to provide an improved method and apparatus for wrapping objects—herein referred to as "pipe"—with pressure-sensitive tape so as to insure that the tape goes on smoothly and uniformly with predetermined overlap. A further object of the invention is to facilitate the wrapping of pipe with pressure-sensitive tape in cold weather and to assure proper adhesion of the tape to the pipe without the need of preheating the pipe.

Other objects and advantages of the invention will be apparent from the following description and claims and from the accompanying drawings which illustrate, by way of example, a preferred embodiment of the invention.

In the drawings:

Fig. 1 is a perspective view of apparatus for applying

2

pressure-sensitive adhesive tape to pipe, in accordance with the invention, certain interior portions being shown in dotted lines.

Fig. 2 is a cross section taken approximately on the line 2—2 in Fig. 1, the roll of tape being shown in dotted lines to avoid obscuring portions of the apparatus.

The apparatus illustrated by way of example in the drawings comprises an enclosure 1 shown in the form of a prismatic case or box of approximately square cross section. The enclosure 1 has opposite end walls 2, side walls 3 and 4, bottom 5 and top or cover 6. The enclosure is preferably formed from strong, heat-insulating material, for example plywood, cardboard, fiber board, pressed wood or plastic. The end walls 2 are shown approximately square and have central apertures 8, the apertures of the opposite ends being in alignment with one another. The cover 6 is arranged so that it can be removed or opened. For example, it is hingedly attached to one of the end walls by means of hinges 9, a catch 10 being provided at the opposite end of the cover to hold the cover in closed position. One of the side walls 4 is provided with an elongated slot 12 having a length greater than the width of the tape that is to be applied. In the construction shown in the drawings, the slot 12 is formed by recessing a portion of the upper edge of the side wall 4, the upper edge of the slot being formed by an edge 13 of the cover 6 that is spaced from the recessed portion of the upper edge of the side wall 4.

The enclosure 1 is large enough to receive a roll of pressure-sensitive adhesive tape 15, the roll being shown in dotted lines in Figs. 1 and 2 and indicated by the reference numeral 15. The roll has an axial bore or hole 16 and is disposed in the enclosure so that the axial bore of the roll is aligned with the apertures 8 in the opposite end walls 2. A shaft 18 is inserted through the apertures 8 in the end walls 2 of the enclosure 1 and through the axial hole 16 of the roll 15. The shaft is longer than the enclosure 1 so that the end portions of the shaft project out beyond the end walls 2. The diameter of the shaft is somewhat less than that of the apertures 8 and the hole 16, so that the shaft is rotatable and movable axially relative to the enclosure 1 and the roll of tape 15. Spacing sleeves 20 surround the shaft 18 and are disposed, respectively, between the opposite ends of the roll of tape 15 and the end walls 2 of the enclosure 1 so as to position the roll and keep it approximately centered between the end walls. It will be seen that the roll of tape 15 is rotatably supported in the enclosure 1 by the shaft 18 and is positioned in an axial direction by the spacing sleeves 20 so that the ends of the roll are spaced from the end walls 2 of the enclosure.

The slotted side wall 4 of the enclosure 1 is adapted to engage the pipe during application of the tape, as described more fully below. To prevent its being abraded by the pipe, the side wall 4 is at least partially covered by a wear plate 22 made of abrasion-resistant material, for example metal. While the wear plate 22 may, if desired, cover the entire side wall 4—except for the slot 12—it ordinarily suffices for it to cover only a central zone extending the length of the side wall, as illustrated in Figs. 1 and 2. The drawings also illustrate the provision of rollers 23 adapted to engage the pipe. The rollers 23 are shown arranged in pairs, with one pair disposed near one end of the enclosure 1 and the other pair disposed near the opposite end of the enclosure. The two rollers of each pair are spaced laterally from one another. The rollers 23 are rotatably mounted on the side wall 4, for example by means of pins 24 extending between spaced ears or lugs 25 bent up from the wear plate 22. The axes of the rollers 23 are preferably parallel to one another and disposed at a slight angle to a plane passing through the axis of the shaft

18 and midway between the rollers of each pair, i. e. a horizontal plane passing through the axis of the shaft 18, as illustrated in Fig. 2. While the slotted side wall 4 of the enclosure has been shown as being provided both with a wear plate 22 and with rollers 23, it will be understood that it may alternatively be provided only with one or the other. If the side wall 4 is sufficiently resistant to abrasion, both the wear plate 22 and the rollers 23 may be omitted.

It has been found that, if the pressure-sensitive adhesive tape is kept warm, it can satisfactorily be applied to pipe in cold weather and will adhere properly to the pipe, even though the pipe itself is cold. In order to keep the tape warm, one or more heaters are provided in the heat-insulated enclosure 1. The heater or heaters are properly disposed to apply a suitable amount of heat to the tape. In the embodiment illustrated in the drawings, there are two heaters 30 disposed at opposite ends of the enclosure. The heaters are selected to provide a predetermined amount of heat over a substantial period of time, for example several hours. Suitable heaters for this purpose are pyrophoric or catalytic heaters using hydrocarbon fuels such as benzine or white gasoline. A flameless catalytic heater of the pocket hand warmer type has been found satisfactory for this purpose. Each heater has a metal case with a plurality of openings 31 for admitting air to the heater. Suitable openings 32 corresponding approximately in position to the holes 31 of the heater case are provided in the end walls 2 of the enclosure 1. Means is provided for releasably holding the heaters 30 in position in the enclosure 1. As shown in the drawings, the holding means for each heater comprises a small spiral spring 33 fastened at its ends to the enclosure wall, for example by small screw eyes 34.

The steps in applying pressure-sensitive adhesive tape to pipe in accordance with the invention are as follows. A roll of tape is positioned in the enclosure 1, as described above, and an end portion of the tape T is brought out through the slot 12 in the side wall 4. The shaft 18 is inserted through the openings 8 in the end walls of the enclosure and the axial hole 16 in the roll of tape with spacing sleeves 20 maintaining the roll in proper axial position. The heaters 30 are ignited or otherwise started and placed in the holders 33. The end portion of the tape is adhesively affixed to the pipe. The operator then grasps the projecting end portions of the shaft 18 and, using these portions as handles, moves the enclosure 1 with the tape contained therein round and round the pipe. The axis of the shaft 18 is kept approximately parallel to the axis of the pipe. As the shaft 18 is carried around the pipe, the roll 15 of tape can turn around the axis of the shaft as the tape is unrolled. The slotted side wall 4 of the enclosure is held in contact with the pipe as the shaft 18 is carried around the pipe, the enclosure being rotatable on the shaft so that the side wall 4 remains approximately tangential to the pipe. Abrasion of the side wall 4 by the pipe—which may be rough—is prevented by the wear plate 22. When the side wall 4 is provided with rollers 23, the rollers roll around the pipe as the tape is wrapped on. By positioning the rollers 23 at an angle, as described above, the enclosure 1 containing the tape is caused to move axially along the pipe as it travels around the pipe, the amount of axial travel or "lead" being chosen so as to provide predetermined overlap of successive convolutions of the tape. The amount of overlap can also be accurately controlled by providing one or more indices on the enclosure 1, such as peripherally extending lines 35, 36 and 37 (Fig. 1.) By maintaining one or another of the indices 35, 36 or 37 at the edge of the preceding convolution of tape, the amount of overlap of the tape is accurately regulated. If the central index 36 is used, the tape will overlap by half its width. Greater or lesser amount of overlap is obtained by using other of the indices. While

the shaft 18 normally projects from both ends of the enclosure 1, it is movable axially relative to the enclosure so as to permit the enclosure to be brought up close to an obstacle when, for example, it is desired to wrap a portion of pipe near a wall, bulkhead, flange, or other obstruction.

In cold weather, the heaters 30 maintain the tape in a predetermined temperature range, so that it will adhere securely to the pipe, even though the pipe itself is cold. When using "Dressertape," it is desirable to maintain the temperature of the tape in the range between 75° F. and 80° F.

It has been found that, with an outside temperature below freezing, for example around 28° F., the temperature in the enclosure can be maintained at 75° F., to 80° F., by the use of two pocket hand warmers, as illustrated and described.

It will be understood that the invention is not limited to the apparatus shown by way of example in the drawings. Moreover, terms defining the relation of the several parts, for example "parallel," are used in a general descriptive sense rather than in an exact sense and are intended to cover arrangements that are substantially or approximately as described. Various modifications within the scope of the appended claims will be apparent to those skilled in the art.

What we claim and desire to secure by Letters Patent is:

1. In apparatus for applying pressure-sensitive adhesive tape to pipe, said tape being supplied in a roll with an axial hole, an enclosure having opposite end walls with aligned central apertures and a side wall having an elongated slot parallel to the axis of said apertures, said enclosure being sufficiently large to receive said roll with the axial hole of the roll aligned with said apertures and said slot being longer than the width of said tape, a heater in said enclosure, means for releasably holding said heater in position in said enclosure, and a shaft extending through said apertures and hole, said shaft being longer than said enclosure and being rotatable and axially movable relative to said roll and enclosure, the end of said tape being led out through said slot and the tape being wrapped on the pipe by carrying said shaft, with the roll and enclosure thereon, around the pipe while maintaining the shaft approximately parallel to the axis of the pipe and the slotted side of the container in contact with the pipe, the roll and enclosure rotating on said shaft as it is carried around the pipe.

2. In apparatus for applying pressure-sensitive adhesive tape to pipe, said tape being supplied in a roll with an axial hole, an enclosure having opposite end walls with aligned central apertures, a side wall having an elongated slot parallel to the axis of said apertures and an openable cover, said enclosure being sufficiently large to receive said roll with the axial hole of the roll aligned with said apertures and said slot being longer than the width of said tape, a catalytic heater in said enclosure, means for holding said heater in position in said enclosure, the wall of said enclosure having openings therein to supply air for said heater, and a shaft extending through said apertures and hole, said shaft being longer than said enclosure and being rotatable and axially movable relative to said roll and enclosure, the end of said tape being led out through said slot and the tape being wrapped on the pipe by carrying said shaft, with the roll and enclosure thereon, around the pipe while maintaining the shaft approximately parallel to the axis of the pipe and the slotted side of the container in contact with the pipe, the roll and enclosure rotating on said shaft as it is carried around the pipe.

3. Apparatus according to claim 2, having two heaters positioned respectively adjacent opposite end walls of the enclosure.

4. In apparatus for applying pressure-sensitive adhesive tape to pipe, said tape being supplied in a roll with an axial hole, an enclosure having opposite end walls with aligned central apertures and a side wall having an elongated slot parallel to the axis of said apertures and an openable cover, said enclosure being sufficiently large to receive said roll with the axial hole of the roll aligned with said apertures and said slot being longer than the width of said tape, a catalytic heater in said enclosure, means for holding said heater in position in said enclosure, the wall of said enclosure having openings therein to supply air for said heater, and a shaft extending through said apertures and hole, said shaft being longer than said enclosure and being rotatable and axially movable relative to said roll and enclosure, the end of said tape being led out through said slot and the tape being wrapped on the pipe by carrying said shaft, with the roll and enclosure thereon, around the pipe while maintaining the shaft approximately parallel to the axis of the pipe and the slotted side of the container in contact with the pipe, the roll and enclosure rotating on said shaft as it is carried around the pipe.

gated slot parallel to the axis of said apertures, said enclosure being sufficiently large to receive said roll with the axial hole of the roll aligned with said apertures and said slot being longer than the width of said tape, a shaft extending through said apertures and hole, said shaft being sufficiently longer than said enclosure to project and provide handholds at both ends of said enclosure and being rotatable and axially movable relative to said roll enclosure, and spacing sleeves surrounding said shaft and disposed between the ends of said roll and the end walls of said enclosure to retain said roll in predetermined position relative to said end walls, the end of said tape being led out through said slot and the tape being wrapped on the pipe by carrying said shaft, with the roll and enclosure thereon, around the pipe while maintaining the shaft approximately parallel to the axis of the pipe and means on the enclosure engaging the pipe and assisting in guiding the enclosure in its movement around the pipe, the roll and enclosure rotating on said shaft as it is carried around the pipe.

5. In apparatus for applying pressure-sensitive adhesive tape to pipe, said tape being supplied in the form of a roll with an axial hole, a box formed with walls of heat-insulating material, said box having opposite end walls with aligned central apertures and a side wall having an elongated slot parallel to the axis of said apertures, said box being sufficiently large to receive said roll with the axial hole of the roll aligned with said apertures and said slot being longer than the width of said tape, a wear plate of abrasion-resistant material at least partially covering the slotted side of the box, a shaft extending through said apertures and hole, said shaft being longer than said box and being rotatable and axially movable relative to said box, the end of said tape being brought out through said slot and the tape being wrapped on the pipe by moving said shaft, with the roll and box supported thereon, helically around the pipe while maintaining the shaft approximately parallel to the axis of the pipe and the wear plate on the slotted side of the box in contact with the pipe, the box rotating on said shaft as it is carried around the pipe.

6. In apparatus for applying pressure-sensitive adhesive tape to pipe, said tape being supplied in the form of a roll with an axial hole, an enclosure having opposite end walls with aligned central apertures and a side wall having an elongated slot parallel to the axis of said apertures, said enclosure being sufficiently large to receive said roll with the axial hole of the roll aligned with said apertures and said slot being longer than the width of said tape, spaced pairs of rollers on the slotted side of said enclosure, the rollers of each pair being spaced laterally from one another and the pairs being spaced axially from one another, and a shaft extending through said apertures and hole, said shaft being longer than said enclosure and being rotatable and axially movable relative to said enclosure, the end of said tape being brought out through said slot and adhesively affixed to the pipe and the tape being thereupon wrapped on the pipe by moving said shaft, with the roll and enclosure supported thereon, in a helical path around the pipe while maintaining the shaft approximately parallel to the axis of the pipe, and the rollers in contact with the pipe, the enclosure rotating on said shaft as it is carried around the pipe.

7. Apparatus according to claim 6, in which said roll-

ers are rotatable about axes that are parallel to one another and are inclined relative to a plane passing through the axis of said apertures and midway between the rollers of each pair, so that the enclosure is moved axially along the pipe with a predetermined lead as it is carried around the pipe.

8. In apparatus for applying pressure-sensitive adhesive tape to pipe, said tape being supplied in the form of a roll with an axial hole, an enclosure having opposite end walls with aligned central apertures, a side wall having an elongated recessed portion in its upper edge extending substantially the full length of said edge and an openable cover having an edge portion spaced from the recess edge portion of said side wall to provide an elongated slot parallel to the axis of said apertures, said enclosure being sufficiently large to receive said roll with the axial hole of the roll aligned with said apertures and said slot being longer than the width of said tape, and a shaft extending through said apertures and hole, said shaft being sufficiently longer than said enclosure to project and provide handholds at both ends of said enclosure and being rotatable and axially movable relative to said enclosure, the end of the tape being brought out through said slot and adhesively affixed to the pipe and the tape being wrapped on the pipe by carrying said shaft, with the roll and enclosure thereon, around the pipe while maintaining the shaft approximately parallel to the axis of the pipe and means on the enclosure engaging the pipe and assisting in guiding the enclosure in its movement around the pipe, the enclosure rotating on said shaft as it is carried around the pipe.

9. In apparatus for applying pressure-sensitive adhesive tape to pipe, said tape being supplied in the form of a roll with an axial hole, an enclosure having opposite end walls with aligned central apertures and a side wall having an elongated slot parallel to the axis of said apertures, said enclosure being sufficiently large to receive said roll with the axial hole of the roll aligned with said apertures and said slot being longer than the width of said tape, and a shaft extending through said apertures and hole, said shaft being sufficiently longer than said enclosure to project and provide handholds at both ends of said enclosure and being rotatable and axially movable relative to said enclosure, the end of said tape being brought out through said slot and adhesively affixed to the pipe, and the tape being thereupon wrapped on the pipe by moving said shaft, with the roll and enclosure supported thereon, around the pipe while maintaining the shaft approximately parallel to the axis of the pipe, means on the enclosure engaging the pipe and assisting in guiding the enclosure in its movement around the pipe and an index on the enclosure cooperating with an edge of the tape wound on the pipe to serve as a guide for moving the enclosure in a direction axial of the pipe as it is moved around the pipe to provide a predetermined overlap of successive convolutions of the tape on the pipe.
